UNITED STATES PATENT OFFICE.

MOSES MANCIL EMERSON, OF ELLENSBURG, WASHINGTON.

TAMPING-ROLLER.

1,371,303.

Specification of Letters Patent. Patented Mar. 15, 1921.

Application filed June 23, 1920. Serial No. 391,252.

To all whom it may concern:

Be it known that I, Moses M. Emerson, a citizen of the United States, and a resident of Ellensburg, in the county of Kittitas, 5 and State of Washington, have invented certain new and useful Improvements in Tamping-Rollers, of which the following is a specification.

My invention relates to improvements in 10 tamping rollers.

The object of the invention is to provide an improved tamping roller which will be effective to completely tamp and roll the entire surface being acted upon and which is 15 of simple and durable construction, reliable and efficient in operation, and easy and inexpensive to manufacture.

Other objects and advantages of the invention reside in certain novel features of 20 construction, combination and arrangement of parts which will be hereinafter more fully described and particularly pointed out in the appended claims, reference being had to the accompanying drawings forming part of this specification, and in which:

Figure 1 is a transverse vertical section of the tamping roller;

Fig. 2 is a side elevational view of one of 30 the tamping units;

Fig. 3 is a longitudinal section of a tamping unit;

Fig. 4 is an elevational view of the periphery or tread of the tamping unit;

Fig. 5 is a detail perspective view of the 35 detachable traction element.

Referring to the drawings it will be seen that my invention contemplates a tamping roller comprising a roller shaft 10 upon which is rotatably mounted a plurality of 40 tamping units, indicated generally at 11.

Each of the tamping units includes a hub designated generally at 12, and rotatably mounted upon the roller shaft. The hub consists of a pair of spaced bearing plates 45 13 one of which is provided with an annular flange 14 extending between the bearing plates and parallel to the axis of the roller shaft. This annular flange serves to space the bearing plates and being disposed adjacent the inner ends thereof it defines an inner cavity 15 and outer cavity 16. Means is provided for securing the bearing plates of each hub together, and this means preferably comprises a plurality or a circular 50 series of bolts 17 which extend through the bearing plates and the annular flange 14 and

which have their heads 18 countersunk into the outer surface of the bearing plates.

A circular series of roller bearings 19 are received and retained in the inner 60 cavity 15 and are thus interposed between the hub and the roller shaft.

A tamping element 20 is slidably mounted in the outer cavity 16. This tamping element is freely rotatable and is freely slideable but all of its sliding movement is constrained to take place along radial lines so that it is slideable radially and only radially. The tamping element consists of a disk 21 having an annular bearing portion at its inner periphery which slidably engages the bearing plates and having in its outer periphery an annular enlargement 70 23. This enlargement may, if it is desired to lighten the tamping element, be provided 75 with an annular cavity 24.

The tread surface of each tamping element is provided with a plurality of traction elements 25 which as seen in Fig. 4 are arranged circumferentially in a pair of 80 parallel transverse rows, the traction units of one row being staggered or arranged alternately with respect to the traction units of the other row. As shown in detail in Fig. 6, each of the traction elements is 85 provided with a shoe 27 constructed of cast steel or chilled iron. Each of these shoes is provided with a shouldered socket 28 which receives the unit 25 and which is riveted thereto by means of rivet pins 29. 90

Means are provided for retaining the tamping units in position on the roller shaft. This means comprise a pair of end plates 30 mounted on the end of the roller shaft and secured in position by lock pins 31. 95

In operation it will be understood that as the tamping roller is pulled along the tamping units will partake independently of rotary movement on the roller shaft. The hubs carrying the tamping elements being 100 easily and freely rotatable by virtue of the roller bearing interposed between these bearings and the roller shafts. Moreover the tamping units themselves may partake of rotary motion with respect to the hubs 105 and they are freely and independently adapted to slide radially in the bearing cavity 16 of the hub. This slideable movement of the tamping element however is at all times constrained to take place along 110 radial lines. This is an important feature of the invention in that it provides for the

proper contacting of the tamping units with the ground and that it insures freedom and independence as between the units, because of the fact that the units are at all times 5 freely spaced from each other. This motion of the tamping units occurs in addition to or along with the motion of the hub which rotating on the roller shaft and traveling forwardly described or traverses 10 a cycloid path.

I claim:

1. In a tamping roller of the character described, a shaft, a plurality of tamping units on said shaft, each of said units comprising a hub rotatably mounted on said shaft and consisting of a pair of spaced bearing plates, one of said bearing plates having an annular flange extending between the plates adjacent the inner end thereof 20 and defining an inner and an outer cavity, means extending through said flange to secure said plates together, roller bearings received in said inner cavity and interposed between the hub and the shaft, a tamping 25 disk having an annular bearing portion at its inner periphery received in the outer cavity for rotary and radial sliding movement with respect to said hub and having an annular enlargement at its outer end, 30 traction elements carried by the tread of said disks, removable traction shoes arranged upon said traction elements, and means for retaining said tamping units on said shaft.
- 35 2. In a tamping roller of the character described, a shaft, a plurality of tamping units on said shaft, each of said units comprising a hub rotatably mounted on said shaft and consisting of a pair of spaced bearing plates, one of said bearing plates having an annular flange extending between the plates adjacent the inner ends thereof and defining an inner and an outer cavity, 40 means extending through said flange to secure said plates together, roller bearings received in said inner cavity and interposed between the hub and the shaft, a tamping 45 disk having an annular bearing portion at its inner periphery received in the outer cavity for rotary and radial sliding movement in said outer cavity, and means for 50 retaining said tamping unit on said shaft.
- 55 3. In a tamping roller of the character described, a shaft, a plurality of tamping units on said shaft, each of said units comprising a hub rotatably mounted on said shaft and consisting of a pair of spaced bearing plates, one of said bearing plates having an annular flange extending between the plates adjacent the inner ends thereof and defining an inner and an outer cavity,

means extending through said flange to secure said plates together, roller bearings received in said inner cavity and interposed between the hub and the shaft, and a tamping element for rotary and radial sliding movement in said outer cavity. 60

4. In a tamping roller of the character described, a shaft, a plurality of tamping units on said shaft, each of said units comprising a hub rotatably mounted on said shaft and consisting of a pair of spaced bearing plates, one of said bearing plates having an annular flange extending between the plates adjacent the inner ends thereof and defining an inner and an outer cavity, roller bearings received in said inner cavity and interposed between the hub and the shaft, 70 and a tamping element for rotary and radial sliding movement in said outer cavity. 75

5. In a tamping unit of the character described, a shaft, a plurality of tamping units on said shaft, each of said units comprising a hub rotatably mounted on said shaft and consisting of a pair of spaced bearing plates, means for securing said 80 plates together in spaced relation, a tamping disk received for rotary and radial sliding motion between said bearing plates and means for retaining said tamping units on 85 said shaft. 90

6. In a tamping roller of the character described, a shaft, and a tamping unit on said shaft including a hub rotatably mounted thereon and consisting of a pair of spaced bearing plates, one of said bearing plates having an annular flange extending between the plates adjacent the inner ends thereof and defining an inner and an outer cavity, means extending through said flange to secure said plates together, roller bearings received in said inner cavity and interposed between the hub and the shaft, and a tamping disk received for rotary and radial 95 sliding movement in the outer cavity. 100

7. In a tamping roller of the character described, a shaft, a tamping unit on said shaft including a hub consisting of spaced bearing plates and a tamping disk received between said bearing plates for rotary and sliding movements with respect thereto. 105

8. In a tamping unit of the character described, a shaft, a plurality of tamping units on said shaft, each of said units comprising a hub and a tamping disk received by said hub for rotary and radial sliding movement 110 with respect thereto, and means for securing said tamping units on said shaft. 115

MOSES MANCIL EMERSON.
